UNITED STATES PATENT OFFICE

JOHN D. BROCK, OF KANSAS CITY, MISSOURI

DESIGN FOR A BRIDGE MEMBER FOR AN OPHTHALMIC MOUNTING

Application filed March 31, 1931. Serial No. 39,311. Term of patent 3½ years.

To all whom it may concern:

Be it known that I, JOHN D. BROCK, a citizen of the United States of America, residing in Kansas City, county of Jackson, State of Missouri, have invented a new, original, and ornamental Design for a Bridge Member for an Ophthalmic Mounting, of which the following is a specification, reference being had to the accompanying drawings forming a part thereof.

Fig. 1 is a face view of a bridge member for an ophthalmic mounting showing my new design, and Fig. 2 is a top edge view of the same.

I claim:

The ornamental design for a bridge member for an ophthalmic mounting, substantially as shown.

JOHN D. BROCK.
